UNITED STATES PATENT OFFICE.

EDGAR W. BREISCH, OF WILKINSBURG, PENNSYLVANIA, ASSIGNOR TO WESTINGHOUSE ELECTRIC & MANUFACTURING COMPANY, A CORPORATION OF PENNSYLVANIA.

HOT-CATHODE APPARATUS.

Application filed November 9, 1918. Serial No. 261,916.

To all whom it may concern:

Be it known that I, EDGAR W. BREISCH, a citizen of the United States, and a resident of Wilkinsburg, in the county of Allegheny and State of Pennsylvania, have invented a new and useful Improvement in Hot-Cathode Apparatus, of which the following is a specification.

My invention relates to electric apparatus embodying heated electrodes of the filamentary type, and it has for its object to provide means whereby electrodes of this character may be made more highly resistant to the deteriorating effects of arc action and to provide means whereby the point of impact of the working arc thereupon may be more or less closely defined and the relative current flow in the two electrode leads adjusted.

20 The single figure of the accompanying drawing is a partially sectional and partially diagrammatic view of a hot cathode rectifier embodying a preferred form of my invention.

25 Electric apparatus is well known wherein an arc within a closed container plays upon an electrode of the filamentary type, this electrode being maintained at incandescence, as by auxiliary heating current, so as to continuously supply electrons to the surrounding space. The container of apparatus of this character may either be highly evacuated or may be filled with inert gases, such as argon or nitrogen. For obtaining 30 rectifying arcs, the container is preferably filled with argon, as in ordinary commercial practice.

In the past, considerable difficulty has been encountered in constructing apparatus 40 of this character that shall be long-lived because of the tendency of the operating arc to localize near one end of the filamentary electrode, this point of excessive arc activity being determined largely by the 45 voltage relations of the supply circuit. The impact of the arc near one end of the filamentary electrode resulted in the flow of the major portion of the load current through the adjacent supply lead, overloading the 50 seal and causing rapid deterioration thereof and of the electrode structure.

I find that, by the use of an impedance device in one of the supply leads of a hot electrode, I may so adjust the potential con-

ditions of the entire circuit as to cause the 55 arc to operate at any desired portion of the electrode, such as the central portion thereof. This electrode portion may then be slightly reinforced in cross section, so as to be more rugged in resisting the arc action, care being 60 taken, however, that the reinforcement in cross section is not such as to materially increase the conductivity of this portion of filament, thus lessening the heating and electron-emissivity thereof. By this means, the 65 resultant current flow in the two supply leads may be equalized and maximum life of the apparatus be thus secured.

Referring to the drawing for a more detailed understanding of my invention, I 70 show a closed container at 1 provided with a filamentary cathode 2 and with an anode 3 of any desired form. Alternating current for the operation of the rectifier thus constituted is supplied from a winding 4. The 75 cathode 2 is connected across a small portion of this supply winding, as at the extreme left-hand end thereof, by suitable leads 5 and 6, the point of attachment of the lead 5 being made adjustable so that the heating 80 current supplied to the filament 2 may be adjusted. The anode 3 is connected to a point near the right-hand end of the supply winding 4 by a lead 7 which may also be adjusted on the winding 4. The lead 7 includes a load 8, such as a storage battery to be charged, and, as the rectifying action of the structure thus described is well known and understood in the art, no further detailed description thereof is deemed necessary. 90

With the elements enumerated to this point, the rectifying arc exhibits a tendency to run near the extreme left-hand end of the filamentary cathode 2 as, under these 95 conditions, the maximum operating electromotive force is made use of, namely, that existing between the extreme left-hand end of the winding 4 and the point of attachment of the lead 7. This action results 100 in the early destruction of the filament 2 near its point of attachment to the leading-in wire and in the overloading of the adjacent seal, and it is, therefore, desirable to shift the arc to the central portion of the filament 2, if possible. To this end, I insert an adjustable impedance device 9, such as a resistor, in the lead 6 so that, if 105

the major portion of the load current attempts to flow out of the device over this lead, it encounters this impedance device, with the consequent establishment of a relatively large impedance drop. The effect of the element 9, therefore, is to force a considerable portion of the arc current through the lead 5. When the adjustment is such that the arc current is substantially 10 equally divided between the two cathode leads, the principal zone of arc impact is toward the center of the filament 2, as is desired.

In some cases, the central portion of the 15 filament may be slightly reinforced in cross section, as indicated at 10, so as to withstand the deteriorating action of the arc. This reinforcement may be accomplished by flashing in an appropriate atmosphere but the 20 reinforcing action should not be carried to such an extent as to do so increase the conductivity of the portion of the filament involved that it will not incandesce, with the attendant production of electrons, at the 25 value of heating current which may be safely carried by the remainder of the hot cathode.

While I have shown my invention in its 30 preferred form, it will be obvious to those skilled in the art that it is not so limited but is susceptible of various changes and modifications without departing from the spirit thereof and I desire, therefore, that only such limitations shall be placed thereupon as are imposed by the prior art or are specifically set forth in the appended 35 claims.

I claim as my invention:

1. In electric apparatus, a filamentary 40 electrode adapted to be heated, means for causing an arc to impinge upon said electrode, said arc carrying a current which is a material portion of the current necessary to heat said filament, and means for, at will, modifying the point of arc impact.

2. In electric apparatus, a filamentary 50 electrode adapted to be heated, means for causing an arc to impinge upon said electrode, the current from said arc through said filament forming all or a substantial proportion of the current necessary to heat said filament to an operative temperature, and means for, at will, modifying the point of arc impact.

3. In electric apparatus, a filamentary 60 electrode embodying a portion of reinforced cross-section, means for causing an arc to operate upon said electrode, and potential-adjusting means for causing said arc to operate principally upon said reinforced portion.

4. In electric apparatus, a filamentary 65 cathode adapted to be heated, means for causing an arc to operate upon said electrode, and current-responsive means for ef-

fecting a substantial adjustment in the relative amounts of arc current flowing from said device through the respective ends of said electrode.

5. In electric apparatus, a filamentary 70 cathode adapted to be heated, means for causing an arc to operate upon said electrode, the current from said arc through said filament forming all or a substantial proportion of the current necessary to heat said 75 filament to an operative temperature, and means for adjusting the relative amounts of arc current flowing from said device through the respective ends of said electrode.

6. In electric apparatus, a filamentary 80 cathode, means for passing heating current therethrough, means for causing an arc to operate upon said electrode, the arc current tending to leave said electrode largely 85 through one terminal thereof, and an adjustable impedance device so disposed as to force a material portion of the arc current to leave said electrode through the remaining 90 terminal thereof.

7. The combination with a source of alternating current, of a rectifier embodying a cathode of the filamentary type and an anode, means for connecting said cathode across a portion of said source, means for 95 connecting said anode and cathode across another portion of said source for the maintenance of a rectifying arc therebetween, and an adjustable resistor in one of the 100 cathode leads for determining the point of arc-impact upon said cathode.

8. The combination with an alternating-current supply winding, of a rectifier embodying a hot cathode of the filamentary 105 type and an anode, connections from each end of said cathode to relatively adjacent points near one end of said supply winding, a connection from said anode to a point in said supply winding removed from said end of said supply winding, whereby a rectifying 110 arc is maintained within said rectifier, and an adjustable resistor in the lead of said cathode most widely removed from said anode connection, whereby the principal point of arc impact on said cathode may 115 be adjusted.

9. The combination with an alternating-current supply winding, of a rectifier embodying a hot cathode of the filamentary 120 type provided with a portion of reinforced cross-section and an anode, connections from each end of said cathode to relatively adjacent points near one end of said supply winding, a connection from said anode to a point in said supply winding removed from said end of said supply winding, whereby a rectifying 125 arc is maintained within said rectifier, and an adjustable resistor in the lead of said cathode most widely removed from said anode connection, whereby the 130

principal point of arc impact on said cathode may be adjusted to lie upon said portion of reinforced cross-section.

10. In electric apparatus, a filamentary cathode adapted to be heated, an anode co-operating therewith, means for establishing an arc therebetween, and adjustable current-responsive means for causing said arc to impinge at will principally upon any 10 one of a number of adjacent points intermediate the ends of said cathode.

11. An evacuated electric tube comprising an anode, a cathode co-operating therewith, means for maintaining said cathode in electron-emitting condition, a pair of leads connected to said cathode at separated points, and external means for effecting a substantial adjustment in the relative amounts of current flowing in said leads. 15

20 12. An evacuated electric tube comprising

an anode, a cathode co-operating therewith means for maintaining said cathode in electron-emitting condition, and a plurality of leads connected to said cathode at separated points, the construction and arrangement 25 being such that substantially more current tends to flow in one lead than in another, said one lead having an impedance sufficient to neutralize said tendency.

13. The method of operating a gaseous 30 discharge device comprising a heated filamentary cathode, which consists in controlling, at will, the current distribution in said cathode to prevent continuous impingement of the discharge upon one portion of said 35 cathode.

In testimony whereof, I have hereunto subscribed my name this 2nd day of Nov. 1918.

EDGAR W. BREISCH.
